UNITED STATES PATENT OFFICE.

GEORGE W. FREY, OF CINCINNATI, OHIO, ASSIGNOR TO THE COMPRESSED WOOD PRESERVING COMPANY, OF CINCINNATI, OHIO, A CORPORATION OF OHIO.

PAVING-BLOCK.

1,299,453.

Specification of Letters Patent.

Patented Apr. 8, 1919.

Application filed April 26, 1918. Serial No. 230,873.

To all whom it may concern:

Be it known that I, GEORGE W. FREY, a citizen of the United States of America, and resident of Cincinnati, in the county of 5 Hamilton and State of Ohio, have invented a new and useful Improvement in Paving-Blocks, of which the following is a specification.

My invention has for an object to produce an improved wood paving block which 10 will prevent the buckling which usually occurs upon expansion due to frost and moisture when a pavement is laid with the ordinary form of wood paving block, and which 15 will assume its normal shape when the moisture evaporates.

A further object is to produce an improved wood paving block which will permit the filling of tar and sand between adjacent blocks to be accomplished more easily and thoroughly than between blocks of ordinary construction.

These and other objects are attained in the wood paving block construction described in the following specification and illustrated in the accompanying drawing in which Figure 1 is a fragmental perspective view of a section of wood block pavement constructed of paving blocks embodying my 30 invention.

Fig. 2 is a perspective view of a paving block embodying my invention.

My improved block is provided with a plane side 3 and a plane end 4. Side 5, opposite side 3, consists of a series of projections 6, extending in one direction from the center of the side and a series of projections 7 extending in opposite directions to the direction of projections 6. Projections 6 and 7 have an elongated and a short side so that they resemble in cross section the shape of saw teeth. The end projections 6^a and 7^a form therefore, acute angles at the corners of the block, instead of the usual right angle corners in the ordinary rectangular wood paving block. End 8 opposite end 4 is formed by cutting a relatively shallow and wide V-shaped groove, which accentuates the acuteness of the angle of the projection 6^a and which forms an acute angle 9, on the opposite side of the block. The projections 6 and 7 and the groove 8 are cut in the direction of the grain, so that the wearing surfaces 10 dis-

close the grain 10 and the heart 11 of the 55 wood.

In laying a pavement in which my improved wood block is employed, the blocks are laid with their ends staggered with relation to one another as shown in Fig. 1, 60 the notched end 8 being located adjacent to plane end 4 of the adjacent block, with the projections 6^a and 9 in abutting engagement with the plane end. The staggered arrangement of the ends of the blocks brings 65 projections 7 in engagement with one-half of the plane face of one block, with the projections 6 in engagement with the adjacent half of the plane face of the next block. This is clearly disclosed in Fig. 1. 70

A decided advantage of a wood block embodying my improved construction, over wood blocks of ordinary construction, is that because of the projections, no means such as parting strips have to be employed 75 for spacing the blocks from one another, since the projections space the blocks so that the filling material may be placed in the V-shaped grooves.

In addition to this the projections, being 80 formed on the side of the block opposite that on which the heart wood 11 is located, have the grain of the wood extending in such a direction that they do not dig into the face with which they contact but may be compressed against the plane faces of the adjacent blocks, should the expansion of the blocks during damp and freezing weather cause the blocks to be pressed more closely together, and when the blocks dry, the projections resume their normal condition. 85

The provision of grooves upon the ends of the blocks spaces them and prevents transverse buckling.

Having thus described my invention, what 95 I claim is;

1. A wood paving block of rectangular shape and having the upper and lower surfaces thereof disclosing end grain, a plane side connecting the upper and lower surfaces, a side opposite the plane side connecting the upper and lower surfaces and provided with two series of projections shaped like saw teeth and extending from the upper to the lower surfaces one series 100 being inclined in one direction and the other series being inclined in the opposite direction. 105

2. A paving block of substantially rectangular shape having a plane side, the side opposite the plane side being provided with a series of projections shaped like saw teeth, a plane end and an end opposite the plane end having an obtuse central groove extending across it.

In testimony whereof, I have hereunto subscribed my name this 23rd day of April, 1918.

GEORGE W. FREY.

Witnesses:

W. THORNTON BOGERT,

WALTER F. MURRAY.
